FRONT PANEL OF A HOUSING FOR ELECTRONIC EQUIPMENT

Burton W. Worral, Orange County, Fla., assignor to
General Dynamics Corporation, a corporation of
Delaware

Filed Aug. 9, 1967, Ser. No. 8,175

Term of patent 14 years

(Cl. D26—1)

The figure is a perspective view of a front panel of a housing for electronic equipment, showing my new design. The housing portion, shown in broken lines, is for illustrative purposes.

I claim:

The ornamental design for a front panel of a housing for electronic equipment, as shown and described.
